[57] CLAIM

The ornamental design for a cab fairing, as shown and described.

DESCRIPTION

FIG. 1 is a perspective view of a cab fairing showing my new design, it being understood that the broken lines are for illustrative purposes only and form no part of the claimed design;

FIG. 2 is a right side elevation view of the cab fairing of FIG. 1, the left side view being a mirror image thereof;

FIG. 3 is a top plan view of the cab fairing of FIG. 1;

FIG. 4 is a bottom plan view of the cab fairing of FIG. 1;

FIG. 5 is a front elevation view of the cab fairing of FIG. 1; and,

FIG. 6 is a rear elevation view of the cab fairing of FIG. 1.
